UNITED STATES PATENT OFFICE.

GEORGE A. BURNHAM, OF SAUGUS, MASSACHUSETTS, ASSIGNOR TO S. B. CONDIT, JR.,
OF BOSTON, MASSACHUSETTS.

CURRENT-CONTROLLING DEVICE FOR ELECTRIC CIRCUITS.

1,124,290.

Specification of Letters Patent.

Patented Jan. 12, 1915.

Application filed November 9, 1910. Serial No. 591,410.

To all whom it may concern:

Be it known that I, GEORGE A. BURNHAM, residing at Saugus, in the county of Essex and State of Massachusetts, have invented an Improvement in Current-Controlling Devices for Electric Circuits, of which the following is a specification.

This invention relates to current-controlling devices for electric-circuits, whereby an excess of current above a maximum demand will be visually indicated. Such a device is especially adapted for use in electric-lighting systems for limiting the number of lamps used at any given time by a consumer, who is paying a flat-rate for a given number of lamps.

The object of the invention is to provide means for opposing the voltage of the supply-current sufficiently to substantially reduce the potential of the current passing to the lamps, said means being controlled by electro-responsive means arranged in series relation with the lamps, whereby when the demand is exceeded the lamps will immediately become dim and remain dim as long as the demand is exceeded, thus visually indicating that the demand is exceeded.

The invention consists essentially in the provision of means for setting up an electro-motive force in opposition to the impressed voltage of the supply-circuit when the demand is exceeded, in such manner that it immediately becomes effective. In the first preferred embodiment of my invention a transformer is employed as a means of setting up an electro-motive force in opposition to the voltage of the supply-current, and means are provided for including said transformer or otherwise rendering it operative when the demand is exceeded and said means is preferably but not necessarily adapted to continuously include said transformer or otherwise render it operative while the demand is exceeded and to return to normal as soon as the exceeded demand ceases.

Figure 1 is a front view of a current-controlling device for electric-circuits embodying this invention. Figs. 2, 3 and 4 are front views of modified forms of current-controlling devices embodying this invention.

Referring to Fig. 1, *a*, *b*, represent the two supply-wires of an electric-circuit, and *c* the lamps or other translating-devices which

are connected in said circuit in any usual or suitable manner.

A transformer, which forms the essential element of the current-controlling device, in said figure comprises a laminated or other form of core *d*, having arranged thereon the primary coil *d'*, and the secondary coil *d''*. Said transformer is designed to be connected in circuit with the translating-devices, so that the supply-current will pass through it, whereby the voltage of the supply-current is opposed to such an extent as to reduce the potential of the current passing to the translating-devices, and in case said translating-devices are lamps, to correspondingly reduce their brilliancy.

As shown in Fig. 1, the secondary coil is adapted to be connected in series relation in one of the supply-circuit wires, and the primary coil is adapted to be connected in multiple between the two supply-circuit wires, both at the supply-side of the translating-devices; and for the purpose of thus connecting said coils in the circuit an electrically-controlled switch is employed. As shown in Fig. 1, said switch consists essentially of a switch-plate *e*, normally engaging a pair of contacts *e'*, *e''*, which is movable to disengage said contacts and to engage another pair of contacts *e³*, *e⁴*, and a solenoid, the movable core or armature *e⁵* of which is connected with said switch-plate for moving it, the coil *e⁶* of which is adapted to be connected in the supply-circuit.

The transformer and electrically-controlled switch may be connected in the circuit in various ways; and in Fig. 1, the secondary coil *d''* is arranged in a circuit-wire *f* leading from the supply-wire *a*, at *f'*, to a point of junction *f''* from which a circuit-wire *f³* leads to the supply-wire *a* at *f⁴*, and the pair of contacts *e'*, *e''*, are arranged in circuit-wires *f³*, *f⁴*, leading from the supply-wire *a* at *f'* to the junction point *f''*, and when the switch-plate *e* is in its normal position said secondary coil is short-circuited; and when moved to disengage the contacts *e'*, *e''*, said secondary coil is in series relation in the circuit and the solenoid-coil *e⁶* is arranged in said circuit-wire *f³* which leads from the junction point *f''* to the supply circuit-wire *a*, at *f⁴*, so that said solenoid coil is at all times in series relation in the circuit and in series with the secondary coil *d''* when the switch *e*, *e'*, *e''* is open. When thus ar-

ranged the supply-current divides at f' , a part passing through the secondary coil to the junction point f^2 and a part passing through the switch-contacts to the junction point f^2 , and the whole passing through the solenoid-coil e^6 .

The primary-coil d' is arranged in a circuit-wire f^7 leading from the supply-wire b at f^8 to the circuit-wire f^3 which includes the pair of switch-contacts e^3, e^4 , and as the switch-plate is normally in engagement with the other pair of switch-contacts the circuit of said primary-coil is normally open, but when closed by a movement of the switch-plate said coil is connected in multiple between the supply-wires a and b .

As the lamps c are turned on the current will pass through the short-circuited secondary-coil and the solenoid-coil, and said solenoid-coil is influenced by it, and as soon as the demand is exceeded by the turning on of more lights than the maximum demand calls for the armature or core of said solenoid will be drawn up or attracted, and the switch-plate moved out of engagement with the contacts e^1, e^2 , and into engagement with the contacts e^3, e^4 . Such movement of the switch-plate opens the short-circuit of the secondary-coil and closes the circuit of the primary coil, so that all the current passes through the secondary-coil, which is in series with the solenoid-coil, and also the current passes through the primary-coil which is in multiple between the two sides of the line, and as a result the voltage of the current supplying the lamps is opposed and the potential thereby substantially reduced, causing the lamps to immediately become dim, and to remain dim as long as this condition prevails. When one or more of the lamps are turned off, so that the demand is not exceeded the switch-plate will be permitted to resume its normal position and the transformer will be immediately rendered ineffective.

Referring to Fig. 2 the supply-wires and translating-devices are the same as in Fig. 1, and a transformer of different form is employed wherein its magnetically charged core is employed as a means to move the switch-plate. In this figure g represents the core which is made of horse-shoe shape; g' the secondary coil arranged on one limb of said core; and g^2 the primary coil arranged on the other limb of said core; and the armature g^3 is pivoted at g^4 , which is movable toward and from the pole, which bears a switch-arm g^5 , engaging one or the other contact g^6 , or g^7 , according as said armature is in its retracted or attracted position. The secondary coil g' is arranged directly in one side, as a , of the supply-circuit, and the primary-coil g^2 is arranged in a circuit-wire h leading from said supply-circuit-wire a to the armature, and

thence to the switch-arm, and a circuit-wire h' leads from the contact g^6 to the supply-wire a , and a circuit-wire h^2 leads from the contact g^7 to the supply-wire b . Normally the armature is retracted and short-circuits the primary coil, thereby preventing loss of voltage due to the impedance of the secondary-coil. By short-circuiting the primary coil the reactance of the secondary coil is substantially nullified, but when the armature is attracted, as it will be when the demand for current is exceeded, the short-circuit is opened by the switch-arm and the primary-coil connected in multiple between the supply-circuit wires a and b , and when thus connected substantially the results heretofore described will follow, *i. e.*, the voltage of the current supplying the lamps will be opposed and the potential thereby correspondingly reduced.

Referring to Fig. 3, the circuit-wire h^2 and contact g^7 , shown in Fig. 2, are omitted, and a back stop i is arranged back of the armature, so that when the armature is attracted the short-circuit of the primary coil will be opened, but said primary-coil will not be connected in multiple between the supply-wires a and b , and in such case the loss of voltage due to the impedance of the secondary-coil is not nullified, and, as a consequence, the voltage supplying the lamps is correspondingly reduced on account of the counter or opposing electro-motive force set up by the self-induction of the secondary-coil.

My invention is also susceptible of other modifications, as for instance, in lieu of employing a transformer as a means of introducing an opposing electro-motive force to reduce the potential of the current, I may employ a motor-generator, as shown in Fig. 4.

In this embodiment of my invention a, b , represent the supply-wires, and c the translating-devices, and j and j' a motor-generator, the generator being connected in the supply-wire b and the motor being connected in a branch wire j^2 leading from the supply-wire a to a contact-member j^3 of a normally open switch, another contact member j^4 of said switch being connected by a circuit-wire j^5 to the supply-wire b . j' represents a solenoid in the supply-wire b , the armature of which is connected with a switch-plate j^6 for closing the switch of the circuit-wires j^2, j^5 , to introduce the motor-generator when the current passing through the coil j' exceeds a predetermined amount. As soon as the motor-generator has started an opposing electro-motive force is introduced which reduces the potential. This modification may be used in connection with a large number of lamps.

While my invention is here illustrated as applied to a two-wire system, of ordinary

construction, it may be applied to a three-wire system of ordinary construction, in a manner well known to electricians.

I claim:—

5 A current-controlling-device for a translating-circuit consisting of a transformer having its secondary-coil arranged in one side of the translating-circuit and normally short-circuited and having its primary-coil
10 arranged in an open circuit which when closed connects it in multiple with the translating-circuit, and means controlled by a current of definite value to open the short-

circuit of the secondary-coil and to close the open circuit of the primary-coil, whereby 15 the voltage of the current passing to the translating-devices is opposed and its potential reduced, substantially as described.

In testimony whereof, I have signed my name to this specification, in the presence of 20 two subscribing witnesses.

GEORGE A. BURNHAM.
